UNITED STATES PATENT OFFICE

CLEMENT HENRY STEVENS, OF FARNHAM COMMON, ENGLAND

ENGINE FRAME

Application filed February 12, 1931, Serial No. 515,343, and in Great Britain April 25, 1930.

This invention relates to the construction of the frames—including columns and bedplates—of vertical Diesel engines, and any like reciprocating engines, and it has for its object the provision of a light steel frame of great strength, and which at the same time avoids the usual bolted joints between cylinders, columns, crank cases and bedplates, in the constructions in which a cast frame is used.

It has already been proposed to construct the framework of an internal combustion engine of vertical plates between the cylinders, the plates being divided at their lower ends to form two legs which are secured to the usual form of cast bedplate and secured at their upper ends to an entablature, common to all the cylinders, on which the latter are supported.

The weakness of this arrangement consists in the fact that the entablature rests upon the top edges of the vertical plates and also in the fact that the bottom edges of the vertical plates are bolted to a cast bedplate, of the usual form, thus perpetuating the horizontal bolted joints in the framing.

The bolts securing these joints are subject to severe tensional stresses at every explosion which takes place in the cylinders.

The present invention entirely eliminates these bolted joints.

According to the present invention a frame for reciprocating engines of the vertical type is constructed of vertical sheet metal plates between the cylinders these plates having gaps in their upper ends through which horizontal plates are passed which form the seatings for the cylinders, the vertical plates being secured together by a wrapper plate or plates extending the whole length of both sides of the engine and from the base to the top and across the bottom of the base below the crank shaft.

A number of alternative constructions, according to the invention, are illustrated in the accompanying drawings wherein Figs. 1 and 2 are sectional front and side elevations respectively of one form of construction; Figs. 3 and 4 illustrate modified constructions for different sizes of engine; while Fig. 5 shows

a detail of the construction used for heavy engines where greater rigidity is desired.

Referring first to Figs. 1, 2 and 4, the construction of the frame is as follows:

Between each pair of cylinders a vertical steel plate 1 is arranged across the axis of the crank shaft, this plate being in one piece from above the cylinder head joints to the lower edge of the base or engine seating. The external contour of the plate follows generally the customary profile of the end view of a vertical engine.

Within the plate 1 are formed or cut two gaps 2 and 3, the upper 2 of which has fitted into it two steel plates 4 and 5, running horizontally the whole length of the engine; of these the upper plate 4 forms the seating 6 for the cylinder heads and cylinders, whilst the lower plate 5 is formed to provide the housing 7 for the lower ends of the cylinders, the position of the cylinders and valves being shown in chain lines in Fig. 1. This arrangement leaves a portion 18 of the vertical frame plate 1 above the plate 4, to act as a girder which receives the upward thrust due to the explosions in the cylinders. Between the two horizontal plates 4 and 5 vertical plates 8 (Fig. 4) are fitted on each side of the cylinders, in order to form the outer casing of the water jackets.

The gap 3 in the lower part of each frame plate is preferably in the form of a circle as shown in Fig. 2, although it may be of any other shape such as that shown in Fig. 4, the radius of its lower edge 9 being struck off from the centre line of the crank shaft and the gap being of such diameter or dimensions that the crank shaft may be passed into position, from either end of the engine, through the gaps 3 in the frame plates 1. The lower edge 9 of each lower gap in the frame plate is provided with a seating 10 upon which the main crank shaft bearing 11 rests and is bolted thereto as indicated, the lower part of the frame plate being provided if necessary with strengthening webs 12 for this purpose.

The lower part 19 of each frame plate forms a girder upon which is received the downward thrust of the explosions in the cylinders.

The construction is thus arranged so that

the crank shaft with the main bearings mounted thereon may be passed through the openings in the lower parts of the frame plates into its position, thus allowing the 5 crank shaft with its bearings to be mounted or dismounted without disturbing any other part of the engine.

In order to connect up the various frame 10 plates one with another, an outer or wrapper plate 13 is fitted extending the whole length of the engine, on both sides, and under the base, and from the base to the top. This wrapper plate may be in one or more pieces and may have the necessary hand holes and 15 inspection door holes 14 cut therein, these holes being covered by the usual doors 15.

The modified construction shown in Fig. 3 is intended for a smaller type of engine than those previously described. In this case instead of having two gaps 2 and 3 in the frame 20 plate 1, they are merged into one large gap 16 and only one horizontal plate 4 is used. But in this case also, the frame plate 1 forms a continuous sling with upper and lower 25 girders 18 and 19, which receive the upward and downward thrusts, due to the explosions in the cylinders. Additional plates or webs 17 extending between the frame plates 1 are provided to increase the rigidity of the frame 30 plate 1 in this case, to counteract the effect of the large gap 16. Additional plates 21, 22, are provided between the wrapper plate 13 and webs 17 and between the two webs 17, respectively to increase the rigidity of the 35 construction.

In the construction shown in Fig. 4, which is intended for an engine in which the pistons are provided with piston rods, crossheads and 40 guide shoes, additional plates 20 forming the crosshead guides or forming seatings for the guides are arranged between the frame plates.

The number of frame plates depends upon the number of cylinders in the engine, but there would be normally one frame plate 45 between each cylinder, and one at each outer end of the engine, but where large units are concerned each frame plate is preferably formed of two or more subsidiary steel plates 1¹, 1² as shown in Fig. 5. These subsidiary plates may be close together at one part and, 50 splayed out at another part as shown, in order to accommodate any special feature of design. In any case each frame plate section, whether of single or multiple plates, 55 is built as a unit in one piece forming a continuous tie surrounding the cylinder heads and crank shaft bearings down to the engine seating.

The whole of each structure above 60 described is connected together by welding, riveting, bolting, or by any other suitable means, whilst stiffeners, ribs, seatings and other details of design can be added as required.

65 By the use of a steel structure as above de-

scribed, a great reduction in the weight of the framework of an engine combined with strength can be achieved, whilst all the usual horizontal bolted connections are avoided.

What I claim as my invention and desire to secure by Letters Patent is:—

1. A frame for a reciprocating engine of the vertical type, comprising vertical sheet metal plates having openings through which are passed horizontal plates which form the seatings for the cylinders, the upper and lower portions of the vertical sheet metal plates forming girders which take the upward and downward thrusts due to the explosions in the cylinders and the vertical plates being secured together by a wrapper plate member extending the whole length of both sides of the engine and from the base to the top and across the bottom.

2. A frame for reciprocating engines of the vertical type, comprising vertical sheet metal plates extending beyond the cylinder head joints and below the crank shaft bearings to constitute girders which receive the forces due to the explosions in the cylinders, 75 openings in each of said plates, horizontal plates forming seatings for the cylinders located in one of said openings, a seating in another of said openings in each plate for receiving the crank shaft bearings, said latter opening being of such a size that the crank shaft with its bearings may be passed longitudinally therethrough, and a wrapper plate member extending the whole length of both sides of the engine and from the base to the top and across the bottom.

3. A frame for reciprocating engines of the vertical type, comprising vertical sheet metal plates extending beyond the cylinder head joints and below the crank shaft bearings to constitute girders which receive the forces due to the explosions in the cylinders, 80 openings in each of said plates, horizontal plates forming seatings for the cylinders located in one of said openings, a seating in another of said openings in each plate for receiving the crank shaft bearings, said latter opening being of such a size that the crank shaft with its bearings may be passed longitudinally therethrough, and a wrapper plate member extending the whole length of both sides of the engine and from the base to the top and across the bottom.

4. A frame for reciprocating engines of the vertical type comprising a plurality of vertical plates between the cylinders, said plates being spaced from one another but secured together and extending beyond the cylinder head joints and below the crank shaft bearings to constitute girders which receive the forces due to the explosions in the cylinders, 95 openings in each of said plates, horizontal plates forming seatings for the cylinders located in one of said openings, a seating in another of said openings in each plate for receiving the crank shaft bearings, said latter opening being of such a size that the crank shaft with its bearings may be passed longitudinally therethrough, and a wrapper plate member extending the whole length of both sides of the engine and from the base to the top and across the bottom.

of such a size that the crankshaft and its bearings may be passed longitudinally therethrough, and a wrapper plate member extending the whole length of the engine frame and from the base to the top, the whole of said structure being welded together.
